UNITED STATES PATENT OFFICE.

HANS LEPPERHOFF, OF READING, PENNSYLVANIA.

FILM-INDICATING SHUTTER DEVICE FOR CAMERAS.

Application filed March 21, 1925. Serial No. 17,277.

To all whom it may concern:

Be it known that I, HANS LEPPERHOFF, a citizen of the United States, residing at Reading, in the county of Berks and State of Pennsylvania, have invented certain new and useful Improvements in Film-Indicating Shutter Devices for Cameras, of which the following is a specification.

This invention relates to shutter-operating mechanism for cameras, in which provision is made for automatically showing the rotation of the film so as to prevent double exposures; and it provides for determinedly rotating an indicator wheel at each reciprocation of the shutter plunger in an improved and simple structure fully described in connection with the accompanying drawings and the novel features of which are clearly defined in the subjoined claims.

20 Fig. 1 is a much enlarged sectional view of a complete device embodying my invention in preferred form.

Fig. 2 is a cross-sectional view on the line 2—2 of Fig. 1.

25 Fig. 3 is a separate view of the cylindrical wall portion of the indicator wheel developed into a flat sheet-metal stamping such as is preferably employed; the engaging projections upon the enclosing casing, and 30 a dotted-line position of the indicator, being also shown so as to make clear diagrammatically the intermittent turning action imparted to the completed wheel by reciprocation of the connected plunger.

35 Fig. 4 is a plan view of the separately formed diametrically arranged plunger connection of the indicator wheel as illustrated in Fig. 1.

Fig. 5 indicates a modified construction in 40 which the indicator wheel and plunger constitute a unitary structure involving turning of the reciprocated plunger with the wheel but essentially embodying my invention.

45 The drawing partly indicates the usual flexible rod 6 by which the shutter is released, the usual flexible tube in which it is moved being omitted. The upper end 6^a of this rod is spring-pressed into engagement 50 with the inserted lower portion 10^a of the plunger stem 10 so as to partake of the reciprocating vertical movement of the latter.

As shown in the preferred construction 55 illustrated the angular-sectioned plunger 10 is non-rotatively guided in the centrally

apertured cap 11 of the cylindrical casing 12; and in addition to operating the flexible shutter-rod 6 as stated carries with it in its reciprocative movement an independently rotatable indicator wheel the periphery of 60 which is provided with a circular series of numbers or indices adapted to be successively shown through an exposing aperture 12^a in the casing wall 12. The cylindrical wall portion 15 of this indicator wheel is 65 preferably formed by a folded-up sheet-metal stamping such as shown in Fig. 3; this being suitably secured to a centrally apertured diametral hub portion 15^a whereby the complete wheel is loosely mounted 70 upon the plunger extension 10^a so as to permit of its being independently rotated while partaking of the reciprocative movement of the plunger.

To provide for imparting determined 75 rotary movements to the reciprocated indicator wheel 15, I employ an adaptation of the crown-wheel-escapement movement, as indicated; both the upper and lower circular edge portions of the cylindrical indicator 80 wall being formed with V-shaped cogs, 15^b 15^c respectively, which successively engage inward projections 12^b and 12^c on the casing wall adapted to serve as fixed pallets; the axial movements of the indicator wheel with 85 the plunger causing rotation thereof as determined by contact of the inclines of the upper and lower cogs successively with the respective fixed projections. This action is diagrammatically indicated in Fig. 3, which 90 shows the incline 16 of an upper cog 15^b in contact with an upper projection 12^b at the extreme upward position of the reciprocated wheel and plunger; the succeeding downward movement thereof in releasing 95 the shutter for exposing film 6, causing the incline 7^b of a lower cog 15^c to contact with a lower projection 12^c and rotate the wheel sufficiently to make its succeeding upward movement result in completing the turning 100 movement so as to expose the succeeding film number (7), through the casing aperture 12^a. It will be noted that the projections 12^b and 12^c are arranged out of vertical alignment so as to insure their proper relation to the inclined cogs successively engaged; and that each reciprocation of the plunger and wheel causes a rotary advance 105 of the latter so as to indicate the number of the film to be next used. 110

Thus each downward and upward movement of the plunger merely carries the indicator wheel vertically, its turning movement being effected entirely by its contact with the fixed projections on the casing.

As specifically set forth this turning movement of the indicator wheel is not only effected entirely by the fixed contacts on the casing, but is free of the plunger which 10 loosely carries it. In the further simplified construction indicated in Fig. 5 this latter feature is dispensed with inasmuch as the indicator wheel is united with the plunger in a unitary structure which however may 15 be satisfactorily usable as described. Other modifications may be readily devised within the scope of my invention as defined in the claims.

What I claim is:

- 20 1. In a shutter device for cameras comprising a shutter-rod plunger; a cylindrical casing having a number-exposing wall aperture and inwardly extending wall projections above and below said aperture, and an indicator wheel carried by said plunger; said indicator wheel having oppositely extending cogs adapted to successively engage said upper and lower wall projections so as to impart a determined rotary movement to the 30 plunger.
2. In a shutter device for cameras comprising a shutter-rod plunger; a cylindrical casing having a number-exposing wall aperture and inwardly extending wall projections above and below said aperture, and an indicator wheel carried by and freely rotatable upon said plunger; said indicator wheel having oppositely extending cogs 35 adapted to successively engage said upper

and lower wall projections so as to impart a determined rotary movement to the wheel at each reciprocation of the plunger.

3. In a shutter device for cameras comprising a shutter-rod plunger; a cylindrical 45 casing having a number-exposing wall aperture, an indicator wheel carried by said plunger, and wheel-engaging means fixed to said casing whereby a determined rotary movement is imparted to the wheel during 50 each reciprocatory movement of the plunger.

4. In a shutter device for cameras comprising a shutter-rod plunger; a cylindrical casing having a number-exposing wall aperture, an indicator wheel carried by and 55 freely rotatable upon said plunger, and wheel-engaging means fixed to said casing whereby a determined rotary movement is imparted to the wheel during each reciprocatory movement of the plunger.

5. In a shutter device for cameras comprising a cylindrical casing having a number-exposing wall aperture, and a shutter-rod plunger; a rotatable indicator-wheel 60 in said casing carried by said plunger and comprising a cylindrical indicator-wall portion separately formed of stamped sheet material and a diametral plunger-connecting portion.

6. In a shutter device for cameras comprising a cylindrical casing having a number-exposing wall aperture, and a shutter-rod plunger; a rotatable indicator wheel 70 in said casing comprising a cylindrical indicator-wall portion separately formed of stamped sheet material, and an attached diametral plate rotatably mounted upon said plunger.

In testimony whereof I affix my signature.
HANS LEPPERHOFF.
